UNITED STATES PATENT OFFICE

2,580,684

PAPER DISPENSER

Benjamin F. Lacy and Fred O. Reichardt, Columbus, Ohio, assignors to Pollock Paper Corporation, Dallas, Tex., a corporation of Texas

Application June 3, 1949, Serial No. 97,006

1 Claim. (Cl. 242—55.2)

1

This invention relates to paper dispensers, and is more particularly concerned with the provision of a dispenser adapted for use in dispensing a household roll of waxed paper wound around a paper tube. It has heretofore been common practice to manufacture rolls of waxed paper weighing approximately one pound and having a width of approximately twelve inches. The present invention contemplates the provision of a dispenser adapted for use in dispensing a roll of waxed paper weighing approximately three and one-half pounds and having a width of approximately fifteen inches in order to save a user time and expense in servicing the dispenser and in wrapping relatively large items.

This invention further contemplates the provision of a dispenser adapted to be simply and inexpensively fabricated from sheet metal to provide a back section adapted to be secured to a wall and formed with forwardly projecting end walls disposed in spaced parallel relation, the inner faces of the end walls being provided with trunnions for engagement within and serving as journals for a tubular paper core of a roll of waxed paper. In mounting a roll of paper for use within the dispenser, the end walls are adapted to be flexed away from each other to permit insertion of the trunnions within the ends of the tubular paper core of the roll. By blanking and forming the back section and end walls from a single sheet of relatively thin steel, the end walls embodying sufficient resiliency to be manually flexed away from each other and then automatically returned to their normal positions after mounting of the roll of paper.

This invention further contemplates the provision of a dispenser embodying a cover hingedly connected to and formed to engage and to extend outwardly and thence downwardly around the end walls provided on the back section of the dispenser, the cover also being formed at its ends with inturned flanges disposed for engagement against the outer faces of the end walls when the cover is in its closed position. By providing inturned flanges on the end of the cover, the end walls are held against flexing movement away from each other, thus maintaining the end wall trunnions in fixed position within the ends of the roll of paper.

This invention further contemplates the provision of a dispenser in which protuberances are provided on the end walls for engagement in apertures formed in the cover flanges when the cover is disposed in its closed position, the cover being disengaged from the protuberances by flex-

2

ing the end walls inwardly toward each other to permit the cover to be raised to its opened position.

This invention embodies other novel features, details of construction and arrangement of parts which are hereinafter set forth in the specification and claim, and illustrated in the accompanying drawing, wherein:

Fig. 1 is a front elevational view illustrating 10 a paper dispenser embodying features of the present invention.

Fig. 2 is an end elevational view of same.

Fig. 3 is a longitudinal sectional view taken along the line 3—3 of Fig. 2.

Fig. 4 is a transverse sectional view taken along the line 4—4 of Fig. 1.

Fig. 5 is a longitudinal sectional view taken along the line 5—5 of Fig. 1.

Fig. 6 is a detail sectional view taken along the line 6—6 of Fig. 2.

Referring now to the drawing for a better understanding of this invention, the paper dispenser is shown as comprising a relatively thin sheet of metal blanked and formed to provide a back wall 6 and end walls 7—7, the end walls being normally disposed in spaced parallel relation. The upper and lower edges of the back wall 6 are turned inwardly to provide stiffening flanges 8—8 extending between the end walls 7—7. Trunnions 9—9 are provided on the inner sides of the end walls 7—7 and are preferably formed of sheet metal to provide annular flanges 11—11 for spot welded engagement to the end walls 7—7. To facilitate locating the trunnions on their end walls prior to the spot welding operation, the end walls have protuberances 12 pressed inwardly to receive and engage the peripheral edge of their respective flanges 11.

A cover 13 is blanked and formed from relatively thin sheet metal and provided with end flanges 14—14 which are disposed to engage the outer surfaces of the end walls 7—7 when the cover is in its closed position. The inner ends of the cover flanges 14—14 are formed with apertures to receive rivets 16, and the end walls 7—7 are also formed with apertures in registry with the cover flange apertures to receive the rivets 16.

Protuberances 17—17 are formed on the outer surfaces of the end walls 7—7 for engagement within apertures 18—18 formed in the cover flanges 14—14 when the cover 13 is in its closed position. A longitudinally extending reinforcing bead 19 is formed in the cover adjacent the lower edge thereof. The lower edge 20 of the cover 13 is serrated at 21—21 adjacent the end walls 7—7.

to facilitate tearing a strip of paper from a roll of waxed paper 22.

The dispenser illustrated and described is particularly suited for use in dispensing a roll of waxed paper 22 wound around a tubular paper core 23. In mounting the roll of paper 22 in the dispenser, the end walls 7-7 are first pressed inwardly to displace the protuberances 17-17 from the apertures 18-18 formed in the cover flanges 14-14. When the protuberances are out of their respective apertures, the cover 13 is pivoted upwardly to its opened position illustrated in dotted outline in Fig. 2. The end walls 7-7 are then flexed away from each other to permit insertion of the trunnions 9-9 into the ends of the tubular cardboard core 23; after which, the end walls 7-7 automatically return to their normal parallel relation positions. The cover 13 is then moved toward its closed position and the end walls 7-7 are pressed inwardly toward each other to permit protuberances 17-17 to enter the apertures 18-18 to secure the cover in its closed position.

When a roll of waxed paper is mounted upon the trunnions 9-9, it will be noted that the flanges 14-14 of the cover 13 act to prevent accidental flexing movement of the end walls 7-7 away from each other. It will further be noted that the serrated portions 21-21 formed on the lower edge 20 of the cover 13 serve to permit a sheet of paper to be severed from the roll 22 regardless of the direction of movement of the sheet during the severing operation.

To facilitate mounting of the dispenser upon a cabinet, wall or the like, portions of the back wall 6 are pressed outwardly at 24, 25 and 26, and these pressed out portions are formed with key slots 27, 28 and 29, respectively, to receive wood screws (not shown).

While this invention has been shown in but one form, it is obvious to those skilled in the art that it is not so limited but is susceptible of various changes and modifications without departing from the spirit and scope of the claimed invention.

We claim as our invention:

A device for holding and dispensing paper from a roll wound upon a tubular core, said device being formed with an open bottom and composed of a sheet of relatively thin metal blanked and formed to provide a back section and an integral pair of flexible end walls projecting in substantially spaced parallel relation from said back section, the upper and lower edges of said back section being turned inwardly to provide reinforcing flanges, said back section including intermediate portions thereof pressed outwardly to form mounting bosses formed with key slots, a second sheet of metal blanked and formed to provide a cover composed of a top and front section and including flanges formed on their opposed ends adapted to enclose the top and front edges of said side walls and to limit outward flexing of the latter, said cover flanges being formed with apertures adapted for engagement with protuberances formed on said end walls, the top of said cover being pivotally connected to said end walls adjacent said back section and the lower free edge of said front section being serrated adjacent said end walls, and a pair of opposing cylindrical trunnions rigidly secured on the inner faces of said end walls and adapted to extend within and serve as journals for said tubular core, said device being adapted to receive a roll of paper when said cover is elevated from engagement with said side walls and the side walls flexed outwardly to permit insertion of said trunnions into said tubular core.
